Inventor,

Chas. W. Bailey

United States Patent Office.

CHARLES W. BAILEY, OF BOSTON, MASSACHUSETTS.

Letters Patent No. 96,538, dated November 9, 1869.

IMPROVEMENT IN DETACHABLE BOOT AND SHOE-HEELS.

The Schedule referred to in these Letters Patent and making part of the same.

To all whom it may concern:

Be it known that I, CHARLES W. BAILEY, of Boston, in the county of Suffolk, and State of Massachusetts, have invented certain new and useful Improvements in Boot and Shoe-Heels; and I do hereby declare the following to be a full, clear, and exact description of the same, reference being had to the accompanying drawings, making a part of this specification, in which—

Figure 1 is a plan of a portion of a boot or shoe-sole, with the heel removed, and showing that portion of the heel-fastening that is permanently affixed to the sole;

Figure 2 is a plan of the heel, removed from the boot, and showing the other parts of the fastening;

Figure 3 is a vertical longitudinal section, through centre of sole, heel, and fastening; and

Figure 4 is a transverse section of the same.

My invention relates, in the first place, to an improved manufacture of detachable wooden heels for boots and shoes; and consists in making the same of wood, with the grain of the wood presented endwise to the wearing-surface, and provided with devices, to be described, by which the heel may be detached from and replaced upon the sole of the boot or shoe, as may be desired by the wearer.

My invention relates, in the second place, to the manner of constructing the connecting-devices for connecting a detachable heel to a boot or shoe, and is an improvement upon the devices for that purpose, described in Letters Patent granted to me, January 29, 1867, No. 61,502; and consists in arranging the plate that is attached to the sole and the plate that is attached to the heel in the same plane, the one enclosing or embracing the other, in combination with suitable latches or latching-devices for securing the two together.

My invention relates, in the third place, to the method of forming the recesses in the heel where required, to receive the connecting-devices, without cutting; and consists in embossing or indenting the fibres of the wood sufficiently to form such recesses by suitable dies, while the wood is so confined as to prevent its splitting.

In the drawings—

A represents a portion of a boot or shoe-sole, and

B, the heel, made of wood, with the grain perpendicular to the tread of the same, and secured to the sole by fastenings, in such a manner that it may be conveniently removed or applied at pleasure, as will be explained.

C is a plate cut from sheet-metal, in the form represented, and provided with the shoulders *a a* and the catches *c c*, formed by being struck up in a die, said recesses being open on the side toward the for-

ward part of the heel, so as to allow the latch to enter the same to secure the heel to the shoe. This plate is securely attached to the sole by nails, as is shown.

D is a U-shaped piece of sheet-metal, which fits accurately within the plate C when the heel is placed in position, and is formed from the piece punched out of the centre of the plate C, by cutting out its centre, and is firmly attached to the upper surface of the heel, in such a position that when it is placed inside of the plate C, the heel shall be in the proper position on the shoe, and the shoulder *b b* abutting against the shoulders *a a*, on the plate C, effectually prevents the heel from being moved on the shoe.

E is a latch or bolt cut from sheet-metal, in the form shown, the outer ends of the several arms of which are depressed below the plane of the body of the same, so that they can pass under the plate D, by which it is held in place, and serve as latches to secure the heel to the shoe, when said arms enter the catches *c c*.

d is a spring, which serves to keep the latches in the catches *c c*.

In constructing this heel, it becomes necessary to form recesses *e e*, for the reception of the spring *d* and the bent ends of the bolt E, and other smaller recesses, *o o*, to receive the heads of the nails, by which the plate C is fastened to the shoe. This is done by embossing or stamping the recesses by crushing the grain of the wood by the use of a die, worked by a press, the wood of which the heel is to be made being held firmly during the operation.

What I claim as my invention, and wish to secure by Letters Patent, is—

1. The detachable heel, made of wood, with the grain of the wood presented endwise to the wearing-surface, and provided with the connecting-devices, and otherwise constructed as herein described, as a new manufacture.

2. The combination of the exterior plate C, which is attached to the sole, and the interior plate D, which is attached to the heel, and fits closely into said exterior plate, so that both are in the same plane, and the latches or catches E, for confining the two plates together in said plane, in a direction perpendicular to it, substantially as described.

3. In the construction of detachable heels, as described, the making of the recesses in the heel to receive the connecting-devices by indenting the wood, instead of cutting it out, substantially as described.

Executed at Boston, this 14th day of May, A. D. 1869.

CHAS. W. BAILEY.
